UNITED STATES PATENT OFFICE.

WILLIAM L. SCHELLENBACH, OF PHILADELPHIA, PENNSYLVANIA, ASSIGNOR
TO HENRY S. HALE, OF SAME PLACE.

REVERSIBLE CAR-SEAT.

SPECIFICATION forming part of Letters Patent No. 645,516, dated March 13, 1900.

Application filed December 22, 1899. Serial No. 741,255. (No model.)

To all whom it may concern:

Be it known that I, WILLIAM L. SCHELLENBACH, a citizen of the United States, residing at the city of Philadelphia, in the county of Philadelphia and State of Pennsylvania, have invented certain new and useful Improvements in Reversible Car-Seats, of which the following is a specification.

My invention has relation to a car-seat, and 10 in such connection it relates to the construction and arrangement of such a seat.

The principal objects of my invention are, first, to provide a car-seat with a back having mechanism for swinging and reversing the same and the seat provided with a cushion having means controlled by the movement of the back for tilting and locking the cushion of the seat; second, to provide a car-seat with an adjustable foot-rail adapted to be raised and 20 lowered in its standards by manipulations of the back, and third, to provide a car-seat with rails and an adjustable leg or cricket adapted to be seated and clamped to any position on the rails for adapting the same to existing 25 structural conditions of the car.

My invention, stated in general terms, consists of a reversible car-seat constructed and arranged in substantially the manner herein-after described and claimed.

30 The nature and scope of my invention will be more fully understood from the following description, taken in connection with the accompanying drawings, forming part hereof, in which—

35 Figure 1 is a front elevational view, partly sectioned and broken away, of a car-seat embodying the main features of my invention, the back of the seat being illustrated in a vertical or intermediate position. Fig. 2 is 40 a vertical sectional view taken on the line xx of Fig. 1, the back of the seat and the cushion being removed. Fig. 3 is an elevational view of the aisle end of the seat, the frame or support for the cushion being sectioned and 45 broken away to more clearly illustrate the mechanism for operating the back and cushion, and the back being shown in one of its inclined positions. Fig. 4 is an enlarged end elevational view of the back-operating mechanism, the two extreme positions of the back and its operating mechanism being illustrated

in full and dotted lines. Fig. 5 is a similar view of the cushion and its tilting mechanism. Fig. 6 is a horizontal sectional view, enlarged, of the frame supporting the cushion, 55 the arch or bridge supporting the cushion, and back-operating mechanisms; and Fig. 7 is a perspective view, enlarged, of one of the sockets or brackets secured to the seat-back and into which a portion of the operating 60 mechanism is adapted to be removably inserted.

Referring to the drawings, the framework of the seat comprises the two end standards a and a' , whereof one, a , is at the aisle end 65 of the seat and forms a continuation of the channeled converging legs a^2 and a^3 , while the other standard, a' , at the wall of the car is supported by channel-beams b' and b^2 , which in turn are supported by legs a^5 and a^6 , similar in construction and arrangement 70 to the legs a^2 and a^3 . Between the two standards a and a' a cushion b is supported in the following manner: The two standards are secured together by the horizontally-arranged 75 channel-beams b' and b^2 , and to the under face of the cushion b , at either end, is secured a plate b^3 , adapted to rock or shift between the two beams b' and b^2 , each plate being beveled, as at b^4 , at either end and the 80 beveled ends resting on a vertical groove b^5 in supports b^6 , secured, respectively, to the two beams b' and b^2 at each of their extremities. The tilting of the plates b^3 and the consequent movement of the cushion b is accomplished 85 by the movement of the back e of the seat, as hereinafter explained. The back e is provided at either end with a bracket, as illustrated in Fig. 7, preferably formed of a plate e' , of metal, having the socket-fingers e^2 and e^3 stamped up out of the plate e and adapted 90 to receive the free end of a lever f . This lever f is slotted at its other end, as at f' , to receive a pin f^2 , carried by a sector-arm f^3 , which arm f^3 at its toothed end is pivotally 95 supported, as at f^4 , upon an arm g . One end of the arm g is pivoted, as at b^4 , upon the bridge or arch d , and the other end of the arm is pivoted, as at g' , to the lever f at a point above the slot f' of the said lever. The 100 teeth f^5 of the sector-arm f^3 are adapted to engage with and travel over a stationary pin-

ion or toothed sector h , formed on or integral with the bridge or arch d . This connection of the seat-back e with the bridge or arch d , by means of the lever f , sector-arm f^3 , and connecting-arm g , permits first of the elevation of the back above the cushion b into a substantially upright or vertical position, as illustrated in Figs. 1 and 2, and then by a further movement of the back to occupy a reversely-inclined position, as illustrated in dotted lines in Fig. 4. In the movement of the seat-back e , the sector-arm f^3 , the toothed end of the arm f^3 is provided with two pins k and k' , located above and below and in a line which passes to one side of the pivotal point f^4 of the sector-arm f^3 . These pins are respectively connected by cords or chains k^2 with a channel-beam k^3 , adapted to slide up and down in either inclined leg a^2 or a^3 on one end of the seat and in corresponding legs a^5 and a^6 at the other end of said seat. At the aisle end of the seat, as illustrated in Fig. 3, these chains or cords k^2 pass directly from a corresponding pin k or k' to a corresponding beam k^3 ; but at the wall end of the seat, as illustrated in Fig. 2 and at the left-hand side of Fig. 1, the cords or chains k^2 pass under pulleys k^4 and over pulleys k^5 to permit the chain to properly connect the pins to the beams.

In the movement of the back e to its successive positions the cushion b is tilted so that its rear is always depressed below the back e and its front elevated. To accomplish this result, the arms g are each provided with two cam projections g^3 , adapted, respectively, as an arm g is moved to first engage one of two rollers g^4 on a tilting plate b^3 , and to thereby swing said plates b^3 and the cushion b , as clearly illustrated in Fig. 5. The beams k^3 serve in their lowermost position as foot-rests for passengers occupying a seat immediately in the rear of said beams.

The adjustable legs or crickets a^5 and a^6 in Fig. 1 are provided with hook-bolts m , which pass over the edge of the channel-beams b' and b^2 and are locked to position at their opposite ends by nuts m' , so that the legs a^6 may be shifted and locked in any desired position along the said rails b' and b^2 to readily adapt the said crickets to any inequalities or other structural conditions present in the arrangement of the car.

Having thus described the nature and objects of my invention, what I claim as new, and desire to secure by Letters Patent, is—

1. In a reversible car-seat, a back and mechanism for reversing the same, a supporting-frame, consisting of two end standards each formed of two converging channeled legs, a

cross-beam adapted to slide up and down in each leg of a standard, and a cord or chain connecting each cross-beam with the mechanism for reversing the back of the car-seat, substantially as and for the purposes described. 65

2. In a reversible car-seat, a back, a lever connected to either end of said back, and having a slotted end, a sector-arm connected at one end to the slotted end of said lever, a bridge-piece supported by the frame of the seat and having a toothed sector in mesh with the toothed end of the sector-arm, and a connecting-arm in pivotal connection at one end with said lever and at its other end with the bridge-piece, said sector-arm being pivoted to said connecting-arm at a point intermediate of its pivoted ends, substantially as and for the purposes described. 75

3. In a reversible car-seat, a back, a lever connected to one end of said back and having a slotted end, a sector-arm connected at one end to the slotted end of said lever, a supporting-frame, consisting of two converging inclined channeled legs and horizontally-arranged channeled beams connecting said legs, a cross-beam adapted to slide up and down in each of said legs, chains or ropes connecting said sector-arms with said cross-beams, a bridge-piece connecting the horizontal channeled beams and having a toothed sector in mesh with the sector-arm, and a connecting-arm pivotally connected at one end to said lever and at its other end to said bridge-piece, said sector-arm being pivoted to said connecting-arm at a point intermediate of its pivoted ends, substantially as and for the purposes described. 95

4. In a reversible car-seat, a back and seat, mechanism adapted to reverse said back and tilt said seat, a supporting-frame, consisting of two end standards each formed of two converging channeled legs, a cross-beam adapted to slide up and down in each leg of a standard, and a cord or chain connecting each cross-beam with the mechanism for reversing the back and tilting the seat, substantially as and for the purposes described. 105

5. In a reversible car-seat, rails and an adjustable leg or cricket adapted to be seated and clamped to any position on said rails, substantially as and for the purposes described. 110

In testimony whereof I have hereunto set my signature in the presence of two subscribing witnesses.

WILLIAM L. SCHELLENBACH.
